UNITED STATES PATENT OFFICE.

THOMAS CLARKSON, OF LONDON, ENGLAND.

STEAM-GENERATOR.

SPECIFICATION forming part of Letters Patent No. 651,593, dated June 12, 1900.

Application filed July 22, 1899. Serial No. 724,818. (No model.)

To all whom it may concern:

Be it known that I, THOMAS CLARKSON, a subject of the Queen of England, residing at London, England, have invented certain new and useful Improvements in or Relating to 5 Steam-Generators, (for which I have made application for Letters Patent in Great Britain, No. 5,775, dated March 16, 1899,) of which the following is a specification.

10 This invention relates to steam-generators, more particularly to that type in which no constant water-level is maintained, the water being fed into one end of a series of coiled tubes connected together and arranged so that 15 steam in a more or less superheated state issues from the other end.

According to this invention the boiler comprises a coil of tubing, into which the water is led, arranged so as to receive heat from the 20 products of combustion just before these products escape into the atmosphere. This feed-heating coil is connected to a coil of tube which is arranged so as to encircle the flame from an oil-burner, which is the source of 25 heat preferably employed. Above the burner lie one above the other a series of involute coils of tube, from one of which the steam-delivery pipe leads. One of the preferred 30 constructions is as follows: Within an insulated casing of suitable shape are formed two cylindrical chambers arranged side by side, with their axes parallel. One of these chambers may be termed the "steam-generating" 35 chamber and the other the "feed-water-heating" chamber. In the latter may be arranged, concentrically, a tube which runs down almost to the bottom of the chamber which is closed and at the top leads into an exhaust-box, through which the products of combustion, 40 can escape into the atmosphere. Beneath the casing inclosing the whole apparatus lies the burner-box, the burner or burners being so arranged as to deliver a mass of flame into the bottom of the steam-generating chamber. 45 Around the central tube in the feed-heating chamber is coiled a tube, into the lower end of which the feed-water is forced by a suitable pump. From the upper end of this coil leads a tube which passes downward and into 50 the bottom of the steam-generating chamber, where it is connected to a tube which is coiled closely around the wall of this chamber, so as to form a water-wall around the actual flame of the burner. The top of this close coil of tube communicates with the lowest 55 of a series of involute coils of tube which are arranged one above the other in the steam-generating chamber. These involute coils are so connected up that the steam generated in the lowermost coils passes up through the 60 series and is superheated to the required extent, being delivered by a suitable tube from the uppermost coil. The products of combustion from the burner pass upward through and around the involute coils, being then deflected by a plate forming the top of the steam-generating chamber downward into the feed-heating chamber, which they traverse from 65 top to bottom, finally passing up the central tube and out into the atmosphere. In the 70 feed-heating chamber the products of combustion pass downward over the feed-water coil, preferably in the opposite direction to which the water is passing through this coil. In another arrangement of the boiler, where 75 space will not allow of the two cylindrical chambers being arranged side by side, the boiler comprises a single chamber of greater length than the steam-generating chamber in the previous case. In the lower part of this 80 chamber is arranged the coil of tube forming the water-wall around the burner and above it the involute coils through which the steam passes. Above the uppermost of these steam-coils are arranged other involute coils through 85 which the feed-water is led, entering at the topmost and issuing at the lowermost, which communicates by a tube with the lowermost coil of the water-wall. The involute coils above mentioned may each be formed separately and connected together by suitable junction-pieces, or they may be formed in pairs, the innermost end of one coil being carried down and continued in a second involute coil beneath the other, the two ends of this 90 double coil being then connected with other elements by suitable junction-pieces or otherwise, as found convenient. It is preferable to arrange the junctions of the coils in such a manner that they may be all situated one 95 above or adjacent to each other in such a way that the portion of the casing covering them may readily be removed to allow of access to the joints.

In the accompanying drawings, Figure 1 is a sectional elevation of a steam-generator constructed in accordance with this invention. Fig. 2 is a plan of the same, the top of the casing being removed. Fig. 3 is a sectional elevation of a modified arrangement of the boiler. Fig. 4 is a plan of a modified arrangement of the involute coils. Fig. 5 is a section on the line 5 5 of Fig. 4.

10 Like letters indicate like parts in all the figures.

A casing composed of twin cylindrical parts A and A' is mounted on a suitable base A², constructed so as to contain some suitable 15 source of heat, such as an oil-burner B. The portion A of the casing contains the steam-generator proper and will hereinafter be termed the "steam-generating" chamber, while the portion A' will hereinafter be termed 20 the "feed-water-heating" chamber. The twin casing A A' is closed by a plate A³, forming part of the base A², an opening A⁴ being left in this plate beneath the steam-generating 25 chamber A to allow of the flame of the burner B having access to the coils of tube within the chamber A. The top of the twin casing is closed by a plate A⁵. Passing through an opening in this plate in the top of the feed-water-heating chamber A' and 30 concentric with the casing of this chamber is arranged a tube C, which reaches nearly to the bottom of the feed-water-heating chamber. A tube D is led into this chamber, conveniently near the top, through the casing A' and coiled 35 around helically within the tube C down to the bottom. Thence the tube D is carried outside the tube C and coiled helically around the outside of the latter to the top in the manner shown in Fig. 1. From the top of the outside 40 of the tube C the tube D is led downward, as at D', either within the feed-water-heating chamber and through the wall of this chamber or outside it and then through the wall of the generating-chamber at A⁶. The tube 45 is now coiled around, as at D², within the casing A, the coils being arranged close together, so as to form a wall around the source of heat. At a suitable point the coiling of the tube in 50 this manner is discontinued, the tube being now arranged in a series of involute coils, as at D³, these coils being superimposed above the source of heat and all connected together, as shown in Fig. 1, to form a continuous conduit, the end of the tube D⁴ for delivering the 55 steam being led out through the wall A of the casing of the generating-chamber. An opening A⁷ is made in the walls of the casings A and A' where these are adjacent to each other, the opening being at or near the top of the 60 casings and of such a size as to allow the products of combustion to pass freely from the steam-generating chamber down into the feed-water-heating chamber, these products of combustion being deflected by the plate A⁸, which forms the top of the casings A and A'. 65 The actual course of the products of combustion is indicated in Fig. 1 by arrows. It will

be seen that these products pass upward around the involute coils of tube D³ and down around the coils D and thence up again within 70 the tube C and out into the atmosphere, a casing A⁸ deflecting the products in a lateral direction.

The modification shown in Fig. 3 is adapted for use where there is not sufficient space to 75 arrange the twin casings A A'. In this modified arrangement a single casing A incloses the whole coil, the tube D being led in at the top of this casing and arranged in a few involute coils and then carried downward, as at 80 D', and through the wall of the casing A, near the bottom of the latter, at A⁶, the tube being then coiled around, as at D², to form the wall around the source of heat. Above the latter, the tube is arranged in involute coils, as at 85 D³, and carried out from the casing A, as at D⁴. In this arrangement the products of combustion pass straight up around the involute coils D³ and D and out through the opening A⁹ in the conical top of the casing A. 90

The involute coils D³ may be arranged so that the contents of the generator either enter at the center or at the outer end, as found convenient. If desired, the coils may be arranged in pairs in the manner shown in Figs. 95 4 and 5, where it will be seen that the tube is coiled from without inward in the lower part and led up and doubled back on itself to form the upper and second part.

The several portions of the tube constituting the continuous conduit D D' D² D³ D⁴ may be joined up together in any convenient manner. In the accompanying drawings no joints are indicated, the coil being shown, diagrammatically, as continuous. In practice, however, the several parts of the coil—such as the several involute coils, the coil forming the wall around the source of heat, and the feed-heating portions—may be formed separate and connected together by joints which, for convenience in having access to them, are arranged in the chamber F, formed by the curved portions of the casings A and A' and a removable door F'. 100

In order to assist the products of combustion 115 in following the prescribed course through the generator, a fan may be arranged to exhaust air from the feed-water-heating chamber, the fan being, for example, arranged within the casing A⁸, as at E, on the top of the generator. The fan may be driven from some moving part 120 of the engine driven by the steam from the generator.

If desired, the top of the feed-water-heating 125 chamber may be closed in and the tube C dispensed with, the products of combustion being then led away from the bottom of the casing A', preferably through an opening in the plate A⁸ or otherwise. The fan in this case is situated in a suitable position in the 130 passage for conducting the exhaust products away.

I claim—

1. In a steam-generator, the combination

of means for generating heat, a steam-generating coil surrounding said means, a superheating-coil communicating with the steam-generating coil and arranged above the same and 5 in the vertical plane of the heat-generator and a feed-water pipe leading into the lower end of the generating-coil, substantially as described.

2. In a steam-generator, the combination 10 of an inclosing casing, means for generating heat, a series of connected coils within the casing arranged in the line of flow of the products of combustion and constituting respectively a feed-water heater, a steam-generator 15 and a steam-superheater, an inlet-pipe leading to the feed-water heater and an outlet-pipe leading from the superheater, substantially as described.

3. In a steam-generator, the combination 20 of means for generating heat, a feed-water heater arranged to be heated by the waste products of combustion from the heater to impart an initial heat to the water, a steam-generator communicating at its lower end 25 with the feed-water heater and a steam-superheating coil connected to the generator and arranged above and in the vertical plane of the heat-generating means, substantially as described.

30 4. In a steam-generator, the combination of means for generating heat, a steam-generator surrounding the same, a feed-water heater communicating with the lower end of the generator, and a superheater arranged in 35 the path of the products of combustion and above the normal water-level in the steam-generator, substantially as described.

5. In a steam-generator, the combination 40 of means for generating heat, a coil of tube constituting a feed-water heater heated by the waste products of the heat-generating means, a coil of tube forming a wall of the tube around the heat-generator and directly connected to the feed-water heater, a series 45 of involute coils superimposed above the heat-generator and directly connected with the wall of tube, all of the coils being connected together so as to form one continuous conduit, as set forth.

50 6. In a steam-generator, the combination of means for generating heat, a coil of tube

constituting a feed-water heater heated by the waste products of the heat-generator, a coil of tube forming a wall of tube around the heat-generator and directly connected to the feed-water heater, a series of involute coils superimposed above the heat-generator and directly connected with the wall of tube, all of the coils being connected together to form one continuous conduit, a twin casing, 60 the parts of which are arranged side by side, one part inclosing the feed-heating portion of the continuous coil and the other part inclosing the rest of the coil and a deflector common to the two parts of the casing to direct the products of combustion into the casing of the feed-heater from its companion casing, substantially as set forth.

7. In a steam-generator, the combination 70 of heat-generating means, a coil of tube constituting a feed-water heater, a coil of tube forming a wall around the heat-generator, a series of pairs of involute coils of tube formed by coiling the tube from without inward carrying it up and doubling it back on itself, 75 the involute coils thus formed being superimposed above the heat-generator, and all of the coils being connected together to form one continuous conduit as set forth.

8. In a steam-generator the combination 80 of means for generating heat, a coil of tube constituting a feed-water heater, a coil of tube forming a wall around the heat-generator, a series of involute coils of tube superimposed above the heat-generator, all the 85 coils being connected together to form a continuous conduit, a twin casing, one part inclosing the feed-heating portion of the coil and the other part inclosing the rest of the coil, a deflector to direct the products of 90 combustion into the casing of the feed-heater from its companion casing, and a fan for sucking the products of combustion out of the feed-water-heating chamber, substantially as described.

In testimony whereof I have hereunto set my hand in the presence of the two subscribing witnesses.

THOMAS CLARKSON.
